NOISE MAKING TUBE

Curtiss J. McCoy, Indianapolis, Ind., assignor to
 Air-Line Mfg. Co., Inc., Indianapolis, Ind., a
 corporation of Indiana

Application April 19, 1941, Serial No. 389,343

10 Claims. (Cl. 46—178)

This invention relates to an air or like operable noise making structure which, however, is neither of whistle or flute type.

The chief object of this invention is to provide a device that inherently is operable by air current flow therein, such interior flow being of reverse character and automatically repetitious when of predetermined intensity.

The chief feature of the invention consists in providing in an elongated tube, near the remote end thereof, a biased seat together with a flap adjacent the seat for intermittent engagement therewith for noise making purposes, such flap being normally constrained toward non-seating engagement and air movable into such engagement, the latter causing air reversal adjacent the seat thereby sucking the flap from the seat for release to its constraint in turn again permitting air flow through the tube for flap seat engagement and noise formation and then flap release and return.

As a toy when a continuous current of air is applied to a tube adjacent the end most remote from the seat and flap there will result a succession of "pops" resembling engine explosions. Mouth application of air should not seal the tube end, and neither should the end of tube nearest the flap and seat be sealed.

A tube of this character can be used as a container for confections, etc.

A tube of this character can be used as a bicycle addition to simulate motorcycle operation.

A tube of this character can be used as an aeroplane kite addition to simulate engine operation thereof.

Other uses of kindred character will readily suggest themselves from the foregoing applications.

Other objects and features will be set forth more fully hereinafter.

The full nature of the invention will be understood from the accompanying drawing, the following description and claims:

In the drawing—

Fig. 1 is a longitudinal sectional view of one embodiment of the invention, full line arrows indicating air flow for noise formation, dotted line arrows indicating reverse air flow for repetitious action, the arcuate dotted line indicating flap member travel.

Fig. 2 is a transverse sectional view taken on line 2—2 of Fig. 1 and in the direction of the arrows, the flap being in idle or normal position.

Fig. 3 is a face view of the seat and the flap member in engagement therewith and is taken in plane parallel to the plane of the seat.

In the drawing 10 indicates an elongated tube having the air entering end or mouth 11 and the remote end 12. Herein, such tube is shown as substantially cylindrical but such form is not

essential. The length of the tube, it has been found, due to the resonating quality thereof determines the tone, the longer tube producing the lower tone. The tube may be of any suitable material. A relatively inexpensive form is that commonly known as a "mailing tube."

Near the remote end 12 and suitably secured therein by press fitting, friction fitting, pinning, adhesive or the like is a smaller tube 13 having a forward face 14 biased to the longitudinal axis of the tube and herein at approximately 45°. Such an insert may readily be formed by taking a tube like tube 13 but not quite twice the required length and then severing such tube medially and on the bias which simultaneously forms identical insert tube members like the tube 13.

Since it is highly desirable that the face 14 be smooth and be in a plane, it is preferred to surface face 14 by the addition of a seat member 15 adhesively secured to that face. Seat member 15 may be of calendered stock such as two ply "Bristol" board or "patent coated newsboard," or may be of calendered face light card board, etc.

Member 15, since tube 10 is cylindrical, has an elliptical opening 16 therein slightly smaller than the opening through tube 13. This is slightly offset (compare tube 13 exposed portions 17 and 18).

A flap member 19 of substantially elliptical character includes a tail or anchoring portion 20. Flap 19 has a hinge crease connection 21 therewith. Immediately adjacent thereto as at 22, see Fig. 1, the flap is curled thereby imparting to the flap constraint to the position same as shown in Fig. 1.

The tail 20 is secured to the rear or remote portion of seat 15 and when the flap 19 fully engages the seat, the opening 14 therethrough is closed.

An air current, intermittent or constant, is applied near mouth 11 of tube 10 and, having a component in the direction of the arrows at the right-hand of the tube mouth, initially flows through the tube, see full line arrows at the remote end 12 of the tube.

Some air, however, gets behind the flap 19 adjacent the tube wall and to escape tends to force entire flap 19 downwardly and rearwardly (referring to Fig. 1). As the free end of the flap moves toward and slightly beyond the longitudinal axis of the tube, substantially the full force of the air stream impinges upon the flapper and slaps it upon the seat member.

This sudden flap engagement creates the sound or "pop" which is resonated by the tube. When the flap is seated, air ceases to flow completely through the tube. The air stream, however, is then deflected by the flap and caused to reverse

its travel. This provides suction on the forward face of the flap member to return it to the position shown in Fig. 1. Then the air again passes through the tube as initially described and the action is automatic and repetitious.

It will be apparent that air can be applied continuously or intermittently and directed toward the mouth of the tube in line therewith or at an angle thereto.

It has also been ascertained that suction applied to mouth 11 is equally as effective in obtaining operation. Moving the tube rapidly through the air toward the right (referring to Fig. 1) will also effect operation. A ninety degree sweep at sufficient velocity will produce about ten distinct "pops." The velocity of tube travel through "dead" air determines the periodicity of the sounds or pops.

One specific form of structure is a tube about 1½" in diameter, 12 inches in overall length and with a 45° bias seat. This angle may vary between 35° and 50°. The length of the tube may vary also.

As shown by dotted lines 30, the tube may have opposed holes therein. These appear to have little, if any, effect on the operation of the device but will raise the tone. Such holes may be utilized to seat opposite ends of a kitchen match type stop member 31. The confection, insertable in mouth 11, thus cannot injure the flap member or seat member, for member 31 serves as a guard or stop.

The flap found satisfactory is of 60# kraft paper. If heavier stock be used the device would be harder to operate, in other words, a greater air velocity would be required. If lighter stock is used it has been found that it may weaken at the hinge and finally tear. Also, it is affected by weather conditions, that is, will warp and also loses its relative bodily stiffness.

It also has been found that the curling of the flap 19 as at 22 insures perfect performance, that is, no "duds" or silence even if the flap became warped. Such curling also imparts "spring" to the flap resulting in quicker opening of hole 14 by the flap and slightly retards the closing movement, as aforesaid, that is, it holds back the closing or seating movement of the flap until past the center and then the remainder of flap travel is accelerated resulting in a louder noise.

While the invention has been illustrated and described in great detail in the foregoing description, the same is to be considered as illustrative and not restrictive in character.

The several modifications described herein, as well as others which will readily suggest themselves to persons skilled in this art, are all considered to be within the broad scope of the invention, reference being had to the appended claims.

The invention claimed is:

1. A noise making tube structure including an elongated tube, a seat forming member therein having a face biased to the longitudinal axis of the tube and positioned closer to one end than the other end, and a curled mounted flap member adapted to completely close the tube when engaging the seat but not ordinarily engaging the same, a stream of air entering the tube from said other end initially causing engagement between flap and seat by impingement of the flap upon said seat and then moving the flap from the seat by suction action of the air stream as it

escapes from the tube at said other end immediately following flap seat engagement.

2. A structure as defined by claim 1, characterized by the flap member being hingedly mounted at one end upon the seat member at a portion closest to the said one end of the tube.

3. A structure as defined by claim 1, characterized by the seat member being similar in general outline to the outline of a similarly biased section of the tube, and the flap member having an outline similar thereto.

4. A tube structure as defined by claim 1, characterized by the elongated tube being of cylindrical character, the seat having inner and outer outlines of elliptical outline, and the flap member having an elliptical outline smaller than the outer outline and larger than the inner outline of the seat.

5. A tube structure as defined by claim 1, characterized by the seat member including a flat sheet with an aperture therethrough and its face engageable with the flap lying in a plane and having a smooth finish.

6. A structure as defined by claim 1, characterized by the addition of a sleeve within the tube and having a biased face to which the seat member is secured.

7. A structure as defined by claim 1, characterized by the addition of a sleeve within the tube and having a biased face to which the seat member is secured, the seat member including a flat sheet with an aperture therethrough and its face engageable with the flap lying in a plane and having a smooth finish.

8. A structure as defined by claim 1, characterized by the addition of a sleeve within the tube and having a biased face to which the seat member is secured, the seat member including a flat sheet with an aperture therethrough and its face engageable with the flap lying in a plane and having a smooth finish, the aperture in the seat member being of lesser area than the opening through the sleeve and slightly offset relative thereto, the hinge mounting of the flap being juxtaposed relative to the portion of greatest eccentricity.

9. A structure as defined by claim 1, characterized by the flap member being hingedly mounted at one end upon the seat member at a portion closest to the said one end of the tube, said flap having an initial curl formation included therein and immediately adjacent the hinge mounting portion for the purpose described.

10. A structure as defined by claim 1, characterized by the flap member being hingedly mounted at one end upon the seat member at a portion closest to the said one end of the tube, said flap having an initial curl formation included therein and immediately adjacent the hinge mounting portion for the purpose described, a sleeve within the tube and having a biased face to which the seat member is secured, the seat member including a flat sheet with an aperture therethrough and its face engageable with the flap lying in a plane and having a smooth finish, the aperture in the seat member being of lesser area than the opening through the sleeve and slightly offset relative thereto, the hinge mounting of the flap being juxtaposed relative to the portion of greatest eccentricity.
